A. COPONY,
DRAFT RIGGING YOKE,
APPLICATION FILED NOV. 30, 1914.

1,243,045.

Patented Oct. 16, 1917.

UNITED STATES PATENT OFFICE.

ALFRED COPONY, OF CHICAGO, ILLINOIS.

DRAFT-RIGGING YOKE.

1,243,045.

Specification of Letters Patent.

Patented Oct. 16, 1917.

Application filed November 30, 1914. Serial No. 874,678.

To all whom it may concern:

Be it known that I, ALFRED COPONY, a citizen of the Austro-Hungarian Empire, residing at Chicago, in the county of Cook and State of Illinois, have invented a certain new and useful Improvement in Draft-Rigging Yokes, of which the following is a full, clear, concise, and exact description, reference being had to the accompanying drawings, forming a part of this specification.

This invention relates to improvements in draft rigging yokes.

An object of the invention is to provide a yoke for draft riggings of railway cars which may be readily attached to and detached from a standard draw bar and which, when in operative position, is prevented by integral means thereon from separating laterally from the draw bar.

The invention furthermore consists in the improvements in the parts and devices and in the novel combinations of the parts and devices, as herein shown, described or claimed.

In the drawing forming a part of this specification, Figure 1 is a top plan view of a yoke embodying my improvements and showing the same attached to a draw bar and indicating in dotted lines the position of the usual stop castings. Fig. 2 is a side elevation of the structure illustrated in Fig. 1. Fig. 3 is a vertical sectional view taken on the line 3—3 of Fig. 2 and Fig. 4 is a horizontal sectional view taken substantially on the line 4—4 of Fig. 2.

In said drawing, 10 denotes a draw bar of M. C. B. specifications, the same having upper and lower shoulders 11—11 and coupler key slot 12. My improved yoke is designated generally by the reference A and, as shown, comprises two like members, which are in the form of links or arms 13—13, each link or arm 13 being provided at its rear end with a shoulder 14 adapted to engage the rear side of a rear follower, said shoulders 14 being braced by a horizontal web or flange 15. At its front end, each arm 13 is provided with a pair of spaced flanges engaging the upper and lower surfaces of the draw bar shank, each of said flanges 16—16 being provided at its rear end with a shoulder 17 adapted to coöperate with the adjacent shoulder 11 on the draw bar. Each pair of flanges 16—16 is connected by a vertical web, which has a curved

inwardly extending portion 18 and an outwardly curved portion 19 (see Fig. 4). Intermediate each pair of flanges 16—16 and preferably integral with the web 18—19, is an inwardly extended projection or lug 20, which is adapted to enter the elongated key slot 12, said lug or projection 20, at its forward end is provided with an overhang or finger 21, which when the yoke arms are in the position clearly indicated in Fig. 4, overlaps the wall 22 surrounding the key slot 12, there being sufficient clearance between the wall 22 and the adjacent edge 23 of the lug 20 to permit the latter to be moved forwardly in the slot when the parts are being applied or detached.

The yoke arms 13—13 are applied to the draw bar by inserting the lugs 20—20 within the key slots 12 and while the yoke arms 13—13 are at an angle to the line of the draw bar. The yoke arms are then swung inwardly toward each other to bring the shoulders 17—17 thereon in engagement with the shoulders 11—11 and when the yoke arms have been brought into parallel engagement with the draw bar, the overhang or finger 21 will engage the walls 22 surrounding the key slots and thus prevent the yoke arms from separating laterally from the draw bar. As will be understood, the lugs 20—20 are not required to undergo any severe strain, inasmuch as under draft, the forces are transmitted from the draw bar to the arms 13—13 through the shoulders 17 and flanges 16 and under buff the forces are transmitted directly through the draw bar to the front follower (not shown.) In the structure which I have shown, no connection is provided between the rear ends 95 of the yoke arms 13—13 and the same will be held in proper position by means of the gear proper and the stop castings in which the yoke arms work. The arrangement is very simple and provides an easy means of attachment to the draw bar and without the necessity of keys or the usual rivets.

I claim:

1. A yoke for railway draft riggings which comprises two members, each having an inwardly extended lug at the front end thereof adapted to engage in a coupler key slot of a draw bar, each of said lugs having a longitudinally extended inner end adapted to engage a wall of said key slot to prevent lateral separation of the yoke members from the draw bar.

2. In a yoke for railway draft riggings, two horizontally arranged arms, each of which is provided at its front end with an inwardly extending lug arranged to enter the coupler key slot of a draw bar, each of said lugs having integral means adapted to overlap the edge of the wall forming said key slot and thus preventing lateral separation of the yoke arms from the draw bar.
- 10 3. A yoke of the character described, comprising two arms each of which is provided at its forward end with upper and lower shoulders arranged to engage the usual shoulders on a draw bar, each of said members being further provided with an inwardly extending lug arranged to enter the coupler key slot of a draw bar, the lug having an overhang to engage the edge of the wall surrounding the key slot.
- 15 4. A yoke for railway draft riggings comprising two members, each of which is provided at its forward end with an inwardly extending hook-like lug arranged to enter a coupler key slot and when in operative position preventing lateral separation from the draw bar.
- 20 5. A yoke for railway draft riggings comprising two members, each of which is provided at its forward end with an inwardly extending hook-like lug arranged to enter
- 25
- 30

a coupler key slot and when in operative position preventing lateral separation from the draw bar, each of said members having also a shoulder at the rear end adapted to engage a rear follower.

35 6. A yoke for railway draft rigging which comprises two horizontally arranged arms, each of which is provided, at its forward end, with an inwardly extending, hook-like lug arranged to enter a coupler 40 key slot.

7. In a yoke of the character described, a link having a shoulder at the rear end adapted to engage a rear follower, upper and lower shoulders at its front end adapted to engage shoulders of a draw bar, and an inwardly extended hook-like lug arranged 45 to enter a coupler key slot.

8. A yoke for railway draft riggings comprising two members, each of which is provided at its forward end with an inwardly extending hook-like lug arranged to enter a recess in the draw bar and when in operative position preventing lateral separation from the draw bar.

50 ALFRED COPONY.
